CLAIM

The ornamental design for a display screen with graphical user interface, as shown and described.

DESCRIPTION

FIG. 1. is a front view of display screen with graphical user interface showing a first embodiment of our new design; FIG. 2. is a front view of display screen with graphical user interface showing a second embodiment of our new design; and,

FIG. 3. is a front view of display screen with graphical user interface showing a third embodiment of our new design. The broken lines illustrate the display screen and form no part of the claimed design. The broken lines illustrate portions of the graphical user interface and form no part of the claimed design. The square grid pattern feature seen in the top right corner of FIGS. 1 to 3 forms no part of the claimed design.
